UNITED STATES PATENT OFFICE.

ROBERT LEWIS JOHNSON, OF HANLEY, ENGLAND.

DESIGN FOR AN EWER.

SPECIFICATION forming part of Design No. 24,725, dated October 1, 1895.

Application filed August 5, 1895. Serial No. 558,328. Term of patent 3½ years.

To all whom it may concern:

Be it known that I, ROBERT LEWIS JOHNSON, a subject of the Queen of Great Britain, residing at Hanley, county of Stafford, England, have invented and produced a new and original Design for Ewers, of which the following is a specification, reference being had to the accompanying drawing, forming a part thereof, in which the ewer is represented in perspective.

The invention relates to a design to be worked in or upon the surfaces of ewers for toilet-sets and for the accessories of such a set; and it consists in the novel configurations herein shown and described.

The design consists in an embossed annular surface, which apparently divides the neck of the ewer from its body, and in a convoluted edge imparted to the mouth of the ewer in which scroll figures are apparently made to intersect each other, the scrolls being substantially reversely arranged, whereby the mouth of the ewer at its edge is given an undulating and somewhat decidedly broken appearance, the scrolls at the central portion of the said margin of the mouth terminating

where they abut in somewhat of an embossed surface.

Another essential feature of the design consists in the base, which is also of a convoluted appearance, substantially matching the margin of the mouth, the base consisting of broad scrolls and offsets of semicircular form from the main scrolls.

In the detail features of the design the body portion is substantially corrugated and decorated with leaf-like scrolls apparently emerging from the base, while the neck is decorated with scrolls of approximate shape, which are distributed above the annular surface, above referred to as separating the neck from the body, and the handle of the ewer is apparently in two sections, finished with a feathery effect.

I claim—

The design for an ewer, substantially as shown and described.

ROBERT LEWIS JOHNSON.
